United States Patent Office

Des. 204,374
Patented Apr. 12, 1966

204,374

CHAIR

Donald L. Bergstrom, 110 S. 18th St., Council Bluffs, Iowa

Filed Apr. 15, 1965, Ser. No. 84,807

Term of patent 14 years

(Cl. D15—1)

Fig. 1

Fig. 2

Fig. 3

Fig. 4

FIG. 1 is a perspective view of the chair of this invention;

FIG. 2 is a side elevational view of the chair, the opposite side thereof having an identical appearance;

FIG. 3 is a rear elevational view thereof; and

FIG. 4 is a top plan view thereof.

The dominant features of my design reside in those portions shown in full lines on the drawing.

I claim:

The ornamental design for a chair, substantially as shown and described.
